Des. 227,764
Patented July 17, 1973

227,764

CAN FOR MOSQUITO REPELLING COILS

Yoshio Katsuda, Osaka, Japan, assignor to Dainippon
Jochugiku Kabushiki Kaisha, Osaka City, Osaka-fu,
Japan

Filed Mar. 3, 1972, Ser. No. 231,800

Term of patent 14 years

Int. Cl. D23—04

U.S. Cl. D23—148

FIG. 1

FIG. 3

FIG. 2

FIG. 4

FIG. 5

FIG. 6

FIG. 7

FIG. 8

FIG. 1 is a perspective view from upside of my new can for mosquito repelling coils with the lid.

FIG. 2 is a perspective view of my invention actually used.

FIG. 3 is a vertical-sectional view taken from the center of FIG. 1.

FIG. 4 is a perspective view from upside of the main body.

FIG. 5 is a perspective view from downside of the main body.

FIG. 6 is a perspective view from upside of the lid.

FIG. 7 is a perspective view from downside of the lid.

FIG. 8 is a perspective view of the internal lid.

I claim:

The ornamental design for a can for mosquito repelling coils, as shown.
